BAFFLE GASIFIER

James L. Breese and Bruce Hayter, Santa Fe,
N. Mex., assignors to Oil Devices, Santa Fe,
N. Mex., a limited partnership of Illinois

Application April 10, 1939, Serial No. 267,021

13 Claims. (Cl. 158—91)

Our invention relates to an improvement in pot type hydrocarbon burners. One purpose is the provision of improved means for preventing deposit of carbon or soot in the burner when the 5 burner is running at low flame.

Another purpose is the provision of a maximum turndown whereby a pilot effect may be obtained.

Another purpose is the provision of improved 10 gasifying means for obtaining the preliminary hydroxylation of the mixture in a pot type burner.

Another purpose is the provision of means for directing a mixture of primary air and vaporized hydrocarbon inwardly toward the central portion 15 of a pot type burner.

Other purposes will appear from time to time in 20 the course of the specification and claims.

We illustrate our invention more or less diagrammatically in the accompanying drawings 25 wherein:

20 Fig. 1 is a vertical axial section;

Fig. 2 is a section on the line 2—2 of Fig. 1; and 25 Fig. 3 is a section similar to Fig. 1 illustrating a pot with a variant form of baffle.

Like parts are indicated by like symbols 30 throughout the specification and the drawings.

Referring to the drawings, 1 indicates any suitable outer shell, drum or the like into the interior of which any suitable means, not herein shown, may be employed for admitting air. 2 is a circumferential support which may be secured to the inner face of the member 1 and which is herein shown as a ring annular in cross section. 3 indicates the mixing chamber or pot proper, which may have a slightly concave bottom 4 and 35 an oil or liquid fuel inlet member 5. The member 3 is shown as having an upper top flange 6 with a down-turned outer flange portion 7 adapted to seat upon the ring 2, whereby the burner pot is supported within the shell 1.

40 The pot is shown as being provided with a plurality of primary air inlet apertures 9 which may be located in rows at various levels. The lowest row of holes, as indicated at 10, may be tipped or distorted whereby the air passing inwardly therethrough is somewhat downwardly as well as inwardly directed. 11 indicates a top row of secondary air inlet apertures, the function of which is to supply additional or secondary air to the upwardly rising mixture of air and vaporized hydrocarbon.

Whereas the process of combustion does not of 45 itself form part of the present invention, it will be understood that in the type of burner herein described a liquid fuel is supplied through the inlet or pipe 5. This liquid fuel is vaporized by the

heat of combustion going on in the upper portion of the pot 3 or thereabove. As the liquid hydrocarbon is vaporized it rises upwardly to and past the level of the various primary air apertures 9 and 10. These apertures serve as an air metering 5 arrangement whereby only sufficient air is supplied to the vaporized hydrocarbon to form a preliminary mixture. It is not until this preliminary mixture receives the additional air supply which enters through the secondary air inlets 11 that 10 final combustion takes place.

The above is a description of the operation of the device when it is being employed at relatively high heating capacity. It is desirable, in burners of this type, to provide for turndown means 15 whereby a low or practically pilot flame may be employed. To obtain this result we supply a generally horizontal baffle member which includes a flat ring 12 having an inner aperture 13. The ring 12 is herein shown as terminating, as at 14, 20 at a radial distance inwardly from the inner face of the pot 3. Secured to the lower face of the ring 12, for example by spot welding, is a second ring generally indicated as 15, which is shown as radially corrugated. It may if desired terminate 25 short of the inner edge of the ring as at 16.

Any suitable means may be employed for supporting the baffle member above described. It may for example be provided with legs 17 which rest upon the bottom 4 of the pot. Or supporting 30 pins or studs 18 may be employed in connection with the wall 3 of the pot.

The edge of the ring 15 is notched or cut away as at 19 at the upper portions of each bend formed by the corrugations of the ring. These 35 cut-away portions 19 are preferably generally V-shaped and are each aligned with one of the downwardly tilted apertures 10. The baffle member as a whole is located preferably at a level slightly below the bottom apertures 10 and it will be 40 understood that a jet of air is downwardly and inwardly directed, through each of the notches 19, from one of the apertures 10. Other apertures 10, which are aligned with lower portions of the ring 15, direct air into the loops or the spaces 45 formed between the flat ring 12 and the corrugated ring 15.

It will thus be observed that some of the air is directed downwardly entirely through and beneath the composite baffle structure above described, whereas some air is directed between the two baffle rings, and finds its way radially inwardly to mix with the mixture of air and vaporized hydrocarbon upwardly rising through the central aperture of the baffle structure. 50 55

The combustion is controlled by controlling the volume of liquid hydrocarbon flowing inwardly through the line 5. Any suitable control may be employed, automatic or otherwise. For purpose 5 of illustration, however, we illustrate in Fig. 2 diagrammatically a hand control valve 25.

In order to align the notches 19 of the corrugated ring 15 properly with the apertures 10, we have provided an alining bar 26, preferably welded to the pot 3, which is received in a corresponding slot 27 formed at the edge of one of the lower corrugations.

Referring to Fig. 3, we illustrate a form of baffle which includes an upper flat ring 30, a lower flat 15 ring 31, and an intermediate corrugated ring 32. This baffle structure may be aligned with any one of the various rows of holes. If the baffle is used as a low turndown pilot baffle, it may properly be aligned with the lowest row of holes, as shown in 20 Fig. 3. The three rings taken together form a series of generally radial tubes. While these tubes are by no means of perfect Venturi shape, experience indicates that they obtain a Venturi result.

25 In this form of the device, the lower row of holes 10, instead of being downwardly tipped as in Fig. 1, is preferably left straight. The baffle is so located in the pot 3 that the tubes formed by the spaces between the three rings are located 30 directly opposite air holes in the pot. The jets of air that come from said holes 10 travel directly through the tubes as near as practically possible in the center.

As the air jets leave the holes in the pot they 35 have a short free travel before actually entering the tubes, as provided by the space illustrated at X in Fig. 3, the corrugated ring 32 and the lower flat ring 31 terminating radially inwardly somewhat from the opposed inner face of the pot 3. 40 If oil vapor is present, these air streams, due to their kinetic effect, will drag oil vapor radially inwardly along the tubes of the baffle structure. This oil vapor and air mixes thoroughly within 45 the tubes and a true hydroxylated oil gas is obtained. This hydroxylated gas is sufficiently rich under all conditions of operation and the velocity of the gas-air mixture in the tube is sufficiently above the rate of flame propagation to prevent 50 flashing back. This gas-air mixture, as it leaves the tubes, burns with an almost clear blue flame.

All of these air jets, as they pick up the gas, create a slight vacuum in the chamber below the baffle or gasifier structure. This vacuum causes a part of the burning gas, as it leaves the ends 55 of the tubes, to be drawn downwardly. This downward flow of hot gases keeps the bottom of the pot quite hot, recirculates the products of combustion, and preheats the carbon dioxide and oil vapor mixture. It has been frequently shown 60 that the mixture of carbon dioxide and the pre-heating of the carbon dioxide gas mixture is advantageous from a combustion standpoint.

While the structure of Fig. 3 can be employed as a pilot, since, located in alignment with the 65 lowest row of holes, it provides a low turndown, it is essentially a gasifier and a hydroxylator and can be located, if desired, at a higher level in the pot. The fact that it can burn at low capacity, due to excellent combustion characteristics, is 70 incidental although desirable.

The baffle structure may be supported upon the pins 18 as illustrated in Fig. 3 or upon legs similar to the legs 17 of Fig. 1.

The upper ring 30 is provided with an aligning 75 slot 34 to receive the aligning bar 26.

It will be realized that whereas we have described and shown a practical and operative device, nevertheless many changes may be made in the size, shape, number and disposition of parts without departing from the spirit of our invention. We therefore wish our drawings to be taken as illustrative and diagrammatic, rather than as limiting us to our precise showing.

We claim:

1. In a pot type hydrocarbon burner, a pot 10 having a bottom and a side wall, said side wall having therein a plurality of primary air inlet apertures located at various levels, means for delivering a liquid fuel to the bottom of said pot, and a centrally apertured baffle, intermediate 15 the top and bottom of said pot, which includes a flat generally horizontal ring and a corrugated ring adjacent thereto the corrugations of said corrugated ring defining with said flat ring a plurality of generally radial passages of a width 20 substantially less than their radial length, effective for conducting air from some of the air inlet apertures to vapors rising from the space below the baffle, each such radial passage being 25 radially aligned with and in communication with one of said primary air inlet apertures.

2. In a pot type hydrocarbon burner, a pot having a bottom and a side wall, said side wall having therein a plurality of primary air inlet apertures located at various levels, means for delivering a liquid fuel to the bottom of said pot, and a centrally apertured baffle, intermediate the 30 top and bottom of said pot, which includes a flat generally horizontal ring and a corrugated ring secured to the bottom thereof, the corrugations 35 of said corrugated ring defining with said flat ring a plurality of generally radial passages of a width substantially less than their radial length, effective for conducting air from some of the air inlet apertures to vapors rising from the space 40 below the baffle, each such radial passage being radially aligned with and in communication with one of said primary air inlet apertures.

3. In a pot type hydrocarbon burner, a pot 45 having a bottom and a side wall, said side wall having therein a plurality of primary air inlet apertures located at various levels, means for delivering a liquid fuel to the bottom of said pot, and a centrally apertured baffle, intermediate the 50 top and bottom of said pot, which includes a flat generally horizontal ring and a corrugated ring adjacent thereto, the corrugations of said corrugated ring defining with said flat ring a plurality of generally radial passages of a width 55 substantially less than their radial length, effective for conducting air from some of the air inlet apertures to vapors rising from the space below the baffle, each such radial passage being radially aligned with and in communication with one of 60 said primary air inlet apertures, said corrugated ring extending to close proximity with the inner face of the side wall, the outer edge of said flat ring being spaced inwardly from the inner face of said side wall.

4. In a pot type hydrocarbon burner, a pot 65 having a bottom and a side wall, said side wall having therein a plurality of primary air inlet apertures located at various levels, means for delivering a liquid fuel to the bottom of said pot, and a centrally apertured baffle, intermediate the 70 top and bottom of said pot, which includes a flat generally horizontal ring and a corrugated ring adjacent thereto, the corrugations of said corrugated ring defining with said flat ring a plurality of generally radial passages of a width 75

- substantially less than their radial length, effective for conducting air from some of the air inlet apertures to vapors rising from the space below the baffle, each such radial passage being 5 radially aligned with and in communication with one of said primary air inlet apertures, said corrugated ring extending to close proximity with the inner face of the side wall, the outer edge of said flat ring being spaced inwardly from the 10 inner face of the side wall, the upper portions of the bends of said corrugated ring being notched in alignment with adjacent air inlet apertures.
5. In a pot type hydrocarbon burner, a pot having a bottom and a side wall, said side wall 15 having therein a plurality of primary air inlet apertures located at various levels, and secondary air inlet means adjacent the top of the pot, means for delivering a liquid fuel to the bottom of said pot, and a gasifier intermediate top and 20 bottom of said pot, and substantially below the secondary air inlet means, said gasifier having portions defining a plurality of restricted air passages extending generally radially inwardly from the inner face of the pot of substantially 25 less width than radial length, each aligned with a primary air inlet aperture in said pot.
6. In a pot type hydrocarbon burner, a pot having a bottom and a side wall, the side wall having therein a plurality of air inlet apertures 30 located at various levels, a generally horizontal pilot baffle located in said pot at a level below the lowest of said air apertures, means for directing air downwardly through said baffle into the space beneath the baffle, and additional means for 35 directing air radially inwardly along the baffle, including a plurality of generally radial passage members.
7. In a baffle structure for hydrocarbon burners, a generally flat ring and a corrugated ring 40 opposed thereto, said corrugated ring having a plurality of generally radial corrugations, the folds of said corrugations engaging one face of said flat ring, said corrugations defining, with the flat ring, a plurality of generally radial restricted air passages of substantially greater radial length 45 than breadth.
8. In a baffle structure for hydrocarbon burners, a generally flat ring and a corrugated ring 50 opposed thereto, said corrugated ring having a plurality of generally radial corrugations, the folds of said corrugations engaging one face of said flat ring, said corrugations defining, with the flat ring, a plurality of generally radial restricted air passages of substantially greater radial length 55 than breadth, said corrugated ring being of smaller diameter than said flat ring.
9. In a pot type hydrocarbon burner, a pot having a bottom and a side wall, said side wall having therein a plurality of air inlet apertures 60 located at various levels, means for delivering a liquid fuel to the bottom of said pot, and a pilot baffle located in said pot at a level below the lowest of said air apertures, said baffle being generally annular in form and having a central aperture, and including a generally flat generally 65 horizontal ring and a corrugated ring, the corrugations of said corrugated ring being generally radial and including portions abutting against the flat ring, the spaces between the flat 70 and the corrugated ring constituting generally radial passages for conducting air from some of the air apertures to vapors rising from the space in the pot below said pilot baffle.
10. In a pot type hydrocarbon burner, a pot having a bottom and a side wall, said side wall having therein a plurality of air inlet apertures located at various levels, means for delivering a liquid fuel to the bottom of said pot, and a pilot 5 baffle located in said pot at a level below the lowest of said air apertures, said baffle being generally annular in form and having a central aperture, and including a generally flat generally horizontal ring and a corrugated ring, the corrugations of said corrugated ring being generally radial and including portions abutting against the flat ring, the spaces between the flat and the corrugated ring constituting generally radial 10 passages for conducting air from some of the air apertures to vapors rising from the space in the pot below said pilot baffle, the outer edge of said baffle being apertured in general radial alignment vertically with apertures located at the lowest level of air apertures. 15
11. In a liquid fuel burner, a pot and means for admitting liquid fuel to the bottom thereof, the pot having in its wall a plurality of primary air apertures located at various levels above the level of the fuel, means adjacent the top of the pot for 20 admitting secondary air to the vaporized mixture of fuel and primary air, and a centrally apertured baffle positioned in said chamber intermediate top and bottom thereof and substantially below the secondary air inlet means, said baffle including a generally flat horizontal plate, and a corrugated plate of sheet metal secured to a face thereof, the corrugations of said sheet metal plate defining a plurality of generally radial passages of a width substantially less than their radial 25 length, each said radial passage being in radial alignment with, and in communication with, a primary air inlet aperture. 30
12. In a liquid fuel burner, a pot and means for admitting liquid fuel to the bottom thereof, the pot having in its wall a plurality of primary air apertures located at various levels above the level of the fuel, means adjacent the top of the pot for admitting secondary air to the vaporized mixture of fuel and primary air, and a centrally 35 apertured baffle positioned in said chamber intermediate top and bottom thereof and substantially below the secondary air inlet means, said baffle including a generally flat horizontal plate, and a corrugated plate of sheet metal secured to the lower face thereof, the corrugations of said sheet metal plate defining a plurality of generally radial 40 passages of a width substantially less than their radial length, each said radial passage being in radial alignment with, and in communication with, a primary air inlet aperture. 45
13. In a liquid fuel burner, a pot and means for admitting liquid fuel to the bottom thereof, the pot having in its wall a plurality of primary air apertures located at various levels above the level of the fuel, means adjacent the top of the pot for admitting secondary air to the vaporized mixture of fuel and primary air, and a centrally apertured baffle positioned in said chamber intermediate 50 top and bottom thereof and substantially below the secondary air inlet means, said baffle defining a plurality of generally radial passages of a width substantially less than their radial length, each said radial passage being in radial alignment 55 with, and in communication with, a primary air inlet aperture. 60
